UNITED STATES PATENT OFFICE

1,983,076

THERMOSTATIC SWITCH

Benjamin E. Getchell, Plainville, Conn., assignor
to The Trumbull Electric Manufacturing Company,
Plainville, Conn., a corporation of Connecticut

Application December 9, 1933, Serial No. 701,714

5 Claims. (Cl. 200—139)

My invention relates to improvements in the invention of my former Patent 1,928,484.

Constructions of this character under some conditions develop difficulties which it is my present object to overcome.

One object is to provide a construction which is more positive in its action.

Another object is to provide a construction which can be made very sensitive.

10 Another object is to provide a construction which cannot be warped out of shape by subjecting to abnormal temperature changes.

Another object is to provide a simple form of construction which can be made and assembled in such a way as to produce reliable and dependable movements under predetermined temperature conditions.

15 In carrying out the invention I provide a warping thermostatic strip or arm with a spring biased hinged switch member at its end as in my former patent and enclose one end of the snapping spring by a cup-like washer which is supported by a knife edge or equivalent arrangement.

The bi-metallic thermostatic strip in this case 20 is supported by one end of a bar which projects from the insulating base and this bar serves not only as a support but as an abutment to limit the warping action of the arm. Additional stops are also preferably provided to limit the action 25 of the arm away from the supporting bar. The arm, as in my former patent, is provided with means for adjusting or varying its action.

Fig. 1 is a plan view of one form of device embodying my invention with the parts in the closed 30 circuit or on position.

Fig. 2 is a side view and partial section of the same.

Fig. 3 is a transverse section on the plane of the line 3—3 of Fig. 2.

40 Fig. 4 is an enlarged fragmentary sectional view showing the contact members separated.

Fig. 5 is an exploded perspective view showing the movable end of the thermostatic arm, the abutment washer and the movable switch member.

The parts are preferably supported by base 7 which also carries circuit terminals 8 and 9 for the stationary and movable switch contacts respectively. The stationary contact 10 is secured 50 to the terminal 8 and projects from the base at a substantially right angle. The movable switch contact member 11 is hinged to the movable end of the bi-metallic thermostatic arm or strip 12 whose other end is secured to and supported by 55 the abutment bar 13. This bar is secured to the

base as, for instance, by riveted portions 14 and 15. The arm is secured to the bar in any suitable manner as, for instance, by a screw or rivet 16 and an adjustment screw 17 is provided for giving an initial set or direction to the warping arm 12. 60 This bar 13 extends substantially the entire length of the thermostatic arm so as to limit the warping movement of the arm in that direction. On the opposite side of the arm I preferably provide stops 18 and 19. 65

The hinged contact member 11 is connected to the thermostatic arm by a hook-like portion 20 which embraces the cross piece 21 so as to permit the arm 11 to swing about this cross piece. The spring 22 surrounds a part of the contact 70 finger between the shoulders 23 and the washer 24. This washer is provided with grooves 25 to receive the knife-like tip 26 of the thermostatic arm.

The washer is preferably provided with a 75 flange 27 which surrounds the larger end of the spring 22 so as to prevent relative displacement. The stationary abutment 28 is provided opposite the contact portion 10 so that the switch member 11 is limited in its movement between 80 the parts 10 and 28.

While I have shown the part 28 as of insulation it is obvious that it might be made conductive to constitute another circuit terminal.

As above pointed out while the construction 85 of my former patent has desirable characteristics there are certain conditions under which such a device may not function as intended. For instance, if we assume that the switch member 11 is moved into the position shown in Fig. 1 90 in response to a decrease in temperature, a further or excessive drop in temperature may cause the thermostatic element 12 to continue to bow in an arcuate form in such a manner as to snap the switch member to the open circuit 95 position which is directly contrary to its intended function. By providing the stationary abutment bar 13 above the thermostatic arm such an excessive warping action is prevented.

The present construction also more accurately 100 relates the hinged switch member 11 to the thermostatic arm by reason of the knife edge support of the washer 24 on the end of the arm and further by reason of the lateral flange of the washer which confines the large end of the 105 spring.

It will also be seen that by the present construction I provide circuit terminals which are riveted directly to the supporting members for the respective switch contacts so that there is 110

no likelihood of a poor electrical connection being established by defective screws or the like.

I claim:

- 5 1. A thermostatic device including an insulating base, a supporting abutment bar carried by the base, a bi-metallic arm secured at one end to said bar and movable at the other end toward and from said bar, said bar serving to limit the warping movement of said arm in one direction, a stop limiting the movement of said arm away from said bar, a stationary contact and a spring pressed switch member hinged to the movable end of said arm and adapted to engage said stationary contact.
- 10 15. 2. A thermostatic device including an insulating base, a supporting abutment bar carried by the base and extending edgewise thereupon, a bi-metallic arm secured at one end to said bar and movable at the other end toward and from said bar and parallel with said base, a stop limiting the movement of said arm away from said bar, two stationary abutments and a spring pressed switch member hinged to the movable end of said arm and adapted to snap between said abutments.
- 20 25. 3. A thermostatic switch including a supporting base, a thermostatic arm having one end supported by said base and having a knife edge at the opposite end, a switch member having a hinged connection with said arm including a

washer having a grooved portion for engagement with said knife edge and a cupped portion, and a spring having one of its ends seated in the cupped portion of said washer and compressed between said washer and a part of said switch member.

80

4. A thermostatic device including an insulating base, a supporting abutment bar carried by the base, a bi-metallic arm secured at one end to said bar and movable at the other end toward and from said bar, said bar serving to limit the warping movement of said arm in one direction, stops near the opposite ends for limiting the movement of said arm away from said bar, a stationary contact and a spring pressed switch member hinged to the movable end of said arm and adapted to engage said stationary contact.

85

5. A thermostatic switching device including a stationary contact, a movable contact, a bi-metallic arm supported at one of its ends and having its opposite end free to move for actuating said movable contact, a compression spring actuated by said arm for imparting a snap action to the contact movement and a cup-shaped washer for seating one end of said spring and disposed between the spring and arm to permit uniform action of the spring, said washer having a grooved portion forming a pivot seat for the movable end portion of said bi-metallic arm.
